United States Patent Office

Des. 192,512
Patented Apr. 3, 1962

192,512

COMBINED SEAT AND TABLE UNIT

George K. Carpenter, 460 Pelham Road,
Haddonfield, N.J.

Filed July 12, 1961, Ser. No. 65,891

Term of patent 7 years

(Cl. D33—14)

FIG. 1 —

Des. 192,512

PAGE 2

FIG. 2 -

FIG. 3 -

FIG. 4.

FIG. 5.

FIG. 6.

FIG. 1 is a front perspective view of a combined seat and table unit embodying my new design;

FIG. 2 is a top plan view;

FIG. 3 is a side elevational view;

FIG. 4 is a bottom plan view;

FIG. 5 is an elevational view of one end; and

FIG. 6 is an elevational view of the opposite end thereof.

I claim:

The ornamental design for a combined seat and table unit, as shown.
